[57] CLAIM

The ornamental design for a housing for interchangeable modular components, such as compasses or thermometers, as shown and described.

DESCRIPTION

FIG. 1 is a perspective view of a housing for interchangeable modular components, such as compasses or thermometers showing our new design;
FIG. 2 is a top plan view thereof;
FIG. 3 is a bottom plan view thereof;
FIG. 4 is a right side elevational view thereof;
FIG. 5 is a left side elevational view thereof; and,
FIG. 6 is a front elevational view thereof, the rear elevational view being a mirror image.

FIG.1

FIG.2

FIG.3

FIG.4

FIG.5

FIG.6
